UNITED STATES PATENT OFFICE.

CURTIS DOUGHERTY, OF CINCINNATI, OHIO, AND CHARLES F. JONES AND DANIEL M. CASE, OF LEXINGTON, KENTUCKY.

SWITCH OPERATING MECHANISM.

1,097,071.

Specification of Letters Patent.

Patented May 26, 1914.

Application filed May 17, 1913. Serial No. 768,205.

To all whom it may concern:

Be it known that we, CURTIS DOUGHERTY, of Cincinnati, county of Hamilton, and State of Ohio, and CHARLES F. JONES and DANIEL M. CASE, of Lexington, county of Fayette, and State of Kentucky, all citizens of the United States of America, have invented certain new and useful Improvements in Switch-Operating Mechanisms, of which the following is a specification.

This invention relates to operating mechanisms for railway switches, and has for an object to produce an improved switch-operating mechanism, which is simple in construction and which overcomes disadvantages and objectionable features ordinarily encountered in such mechanisms.

A further object is to produce a switch-operating mechanism which is reliable in operation and which may be effectively employed in simultaneously throwing and then locking both switches of a cross-over.

A further object is to produce a switch-operating and locking mechanism, in which means are employed for maintaining a substantially constant load on the operating lever, during the operation of the mechanism.

These and other objects are attained by means of the apparatus herein described, and illustrated in the drawings accompanying and forming a part of this application.

In the drawings, Figure 1 is a fragmental plan view of a cross-over provided with a switch-operating mechanism embodying our invention. Fig. 2 is a plan view of an embodiment of our invention, the inclosing casing being shown in section along the line 2-2 of Fig. 3. Fig. 3 is a side elevation of the mechanism shown in Fig. 2 and illustrates the parts in the positions they occupy when the switch is open and locked in the open position; the inclosing casing is shown in section along the line 3-3 of Fig. 2. Fig. 4 is a view corresponding to Fig. 3, and illustrates the positions of the parts when the switch is unlocked, but open. Fig. 5 is a corresponding view showing the parts in the positions they occupy when the switch is closed, but unlocked, and Fig. 6 is a corresponding view showing the positions of the parts, with the switch closed and locked in the closed positions.

The apparatus embodying our invention is adapted to be employed with switches

equipped with standard interlocking devices, and as illustrated in Figs. 2 to 6, inclusive, includes a switch point operating link 7, a lock bar operating link 8, and an operating shaft 9, provided with two operating cranks 11 and 12, which are respectively employed in actuating the links 7 and 8. The cranks are located ninety (90) degrees apart and each crank is provided with a crank pin, which operatively connects one of the links to the shaft. The links are inclosed within a casing 13, and each link is suspended, or mounted, upon the walls of the casing by means of its connecting arms, which project through oppositely located apertures formed in the casing, and co-operate with the apertures in guiding the motion of the link. The crank shaft 9 is journaled in the casing and is provided with an operating lever 14, which is located on the outside of the casing, and is capable of turning the shaft through one hundred and eighty (180) degrees and of thereby actuating the links so that they operate first to unlock the switch point, then to shift the point from one position to the other, and finally to lock the point in position after it has been shifted.

The switch operating link 7 is substantially triangular in shape and is provided with a substantially triangular aperture or slot 15, into which a crank pin 16, mounted on the crank 11 projects, and with which it co-operates. The apex of the triangular slot is notched out, so as to form a recess 17 which is substantially equal in width to the diameter of the crank pin. The edges of the slot, which converge toward and terminate in the recess 17, are curved, and the radius of their curvature is substantially equal to the radius of the circle through which the outermost point of the crank pin moves. The link is so mounted within the casing that the centers of curvature of the curved edges move in a line passing through the center of rotation of the shaft, when the link is moved, and one curved edge or the other of the slot is moved, by the motion of the link, to a position concentric with the shaft. Oppositely extending connecting arms 18 are formed integrally with the link 7 and are so located that they extend on a line with the centers of curvature of the curved edges of the slot. These connecting arms, as has been said, project through oppo-

sitely located apertures formed in the casing 13, and thereby support the link 7 and guide its motion across the casing in response to the operation of the shaft 9. The 5 supporting apertures are so located that the link moves horizontally, in response to the motion of the shaft, and the crank 11 is so mounted on the shaft that it moves from a horizontal position on one side to a horizontal position on the other side of the center, when the lever 14 is thrown from one position to the other. With this construction the link 7 remains stationary during that portion of the motion of the crank in 10 which the crank pin 16 moves along one curved edge of the slot and into the extension 17, and it is then shifted from a position on one side of the center of the crank to a position on the other, while the crank pin is 15 in engagement with the extension 17 and is moving in a substantially horizontal direction. The link 7 remains stationary, after it has shifted its position, and while the crank pin moves along the other curved 20 edge of the slot. Under these conditions the switch point is shifted by the crank, while the crank is moving in a direction substantially parallel to the line of motion of the link, and consequently, the power applied 25 to the crank-actuating lever 14 is most effectively transmitted to the switch point by the link.

The lock bar operating link 8 is provided with a slot 19, which is substantially equal 30 in length to twice the length of the link-actuating crank 12, and the crank 12 is provided with a crank pin 21, which projects into and co-operates with the slot 19 in actuating the link. The end portions of the slot 35 19 are equal in width to the diameter of the pin 21 and their edges are straight and extend parallel to the slot. The intermediate portion of the slot is widened and is provided with curved edges, which are of substantially the same curvature as the circumference 40 through which the pin 21 moves, while the crank is turned from one position to the other. The link 8 is provided with integrally formed oppositely extending connecting arms 22, which are located at an intermediate point, with relation to the slot 45 19, and extend at right angles to the slot. The arms 22, as has been said, extend through apertures formed in the casing 13 and guide the motion of the link. The apertures 50 are so located that the arms extend horizontally, and consequently, the slot 19 extends vertically. The crank 12 is so positioned on the shaft that it moves from a vertical position on one side of the center of 55 rotation of the shaft to a vertical position on the other side of the center, when the lever 14 is thrown from one extreme position to the other. During the motion of the 60 crank 12, and consequently of the crank pin 65

21, the link 8 is first shifted from a position at, or near, the center of the shaft, to a position on one side of the center, and then it is returned to its central position. As the pin 21 moves from one end to the other of the slot 19, it passes first through one end portion of the slot and thereby shifts the link horizontally to such a position, on one side of the center of the shaft, that the center of curvature of one of the curved edges of the slot is concentric with the center of rotation of the shaft 9. The pin then moves into the widened portion of the slot and into engagement with one of the curved edges, but does not actuate the link as it passes along this edge. The link is moved back to its central position by the passage of the pin 21 through the other end portion of the slot, after it has traversed the widened portion of the slot.

The slots 15 and 19 are so arranged, with relation to their co-operating cranks, that the link 8 is first shifted to one side of the center of the shaft 9, then the link 7 is shifted from one to the other side of the center of the shaft, and finally, the link 8 is returned to its central position during the motion of the shaft, occasioned by throwing the lever 14 from one extreme position to the other. This unlocks the switch, then shifts it from one position to the other, and then locks it.

In Fig. 1 we have shown an embodiment of our invention operatively connected to both of the switches of a cross-over and adapted to simultaneously unlock both switches, simultaneously throw them to corresponding positions, and then simultaneously lock them. Each switch is provided with a point-actuating or switch rod 23, to which the link 7 is operatively connected by means of a bell-crank 24 and a rod 25, which is secured to one of the connecting arms 18. Each switch is also provided with a well-known interlocking device, which is adapted to lock the switch points in either of their two positions. As illustrated, each locking device includes a lock rod 27, which is secured to, and is actuated by, the switch points, of one of the switches, and which moves longitudinally through an aperture formed in a lock box or casting 28. The portion of the locking rod which extends through the box 28 is usually rectangular in cross-section and is provided with two transversely extending apertures which are spaced apart a distance equal to the throw of the switch points, and are adapted to move alternately into register with a transversely extending aperture formed in the box 28. A lock bar or pin 29 projects through an aperture in the box 28 and is adapted to pass through one or the other of the apertures formed in the rod 27 and thereby rigidly lock the rod against motion, with relation to the box. The bar or

pin 29 of one of the switches of the cross-over is shown connected to the link 8 by means of a rod 31, a lever 32, and a rod 33, which is connected to one of the connecting arms 22. The lock bar or pin of the other switch is connected to the link 8 by means of a similar system of levers and connecting rods, so arranged that it is moved simultaneously with the other pin. As the link 8 moves to one side of the center of its operating shaft, it withdraws each of the pins 29 from engagement with their coöperating bar 27 and thereby unlocks both of the switches. As the link 7 is shifted from one side to the other of the operating shaft, it simultaneously shifts the points of each switch and either opens or closes both the switches. As the link 8 is returned to its central position by the final motion of the lever 14, it moves both the pins 29 into locking engagement with their corresponding rods 27 and thereby locks both of the switches in the set position.

In addition to the fact that the mechanism illustrated is simpler than the ordinary forms of switch-operating mechanisms known to us, it is also simpler to operate since the switch is unlocked, thrown, and relocked by a single motion of a single lever. The arrangement of the links is also such that they impart a greater amount of motion to the parts operated by them, and consequently, insure the operation of the switches with which they are connected. By increasing the motion of the operating parts, over that of parts in ordinary switches, the power required to shift the switch point may be proportionately reduced by employing motion reducing levers, and there is less danger of the switches failing to operate, due to stretching or yielding of the rods and levers connecting the operating parts with the links. By materially lengthening the stroke of the link 8, and consequently, the motion of the pins 29 over that necessary to lock the switches, we insure either the locking of the switches or an indication that they are unlocked, since the motion of the link 8 is too great to be taken up by yield in the system of rods and levers. In addition to this, the slots in the links are so proportioned that the force required to throw the lever 14 from one extreme position to the other is substantially constant throughout the motion of the lever. This results from the fact that the link 7 is stationary while the link 8 is in motion; that the lever 14 swings through a greater angle, while imparting motion to the switch point operating mechanism, than in most switch-operating devices now in use; and that the link 7 is actuated by the pin 16, while the pin is moving in substantially the same direction as the link. The lever 14 can therefore be easily thrown by a uniform pull from the switchman, and

the operation of the link 7 does not subject it to a sudden jerk, nor is the lever 14 suddenly relieved of its load when the link 7 is released by the pin 16.

In the drawings we have shown means which may be employed in connecting either of the links to near or distant signals. As illustrated, each connecting arm of each link is provided with a lug 35, to which the signal-actuating rod may be connected. It will also be understood that the signal may be actuated from the switch points or from the lock bar, as is customary with such apparatus.

Another feature of our invention is that the links 7 and 8 are so constructed that they may be reversed or inverted in position, without impairing the operation of the mechanism in which they are located. In addition to this, a straight line motion is imparted to each link, and the link can consequently be so connected to the system of operating rods and levers, that this motion will be most efficiently transmitted to the switch.

In accordance with the United States patent statutes we have illustrated and described the preferred embodiment of our invention, but we desire it to be understood that various changes, modifications and substitutions may be made in the device illustrated, without departing from the spirit and scope of our invention, as set forth by the appended claims.

What we claim is:

1. In a switch operating mechanism, a switch point actuating link having an operating slot formed therein, a lock bar actuating link having an operating slot formed therein, a crank shaft, and a separate crank pin, mounted on the shaft, for engaging each operating slot, said slots being so shaped that one link and then the other is actuated during the operation of the crank.

2. A switch operating mechanism comprising a switch point operating link having a pin engaging slot formed therein, a locking device operating link having a pin engaging slot formed therein, a crank shaft for actuating both of said links, separate pins mounted on the crank shaft for engaging the slots in the separate links and for actuating the links during the motion of the shaft, said slots being so formed that each pin is incapable of moving its coöperating link during a portion of its motion therethrough.

3. A switch operating mechanism comprising a switch point operating link having a pin engaging slot formed therein, a locking device operating link having a pin engaging slot formed therein, a rotatably mounted crank shaft having two cranks formed thereon, a separate pin mounted on

each crank, for engaging a slot in each link, and a lever for turning the shaft in either direction through an angle of substantially one hundred and eighty degrees, 5 the slots in said links being so formed that one link is stationary while the other link is moving and the switch point operating link is moved in a straight line substantially parallel to the direction of its actuating 10 pin.

4. A switch operating mechanism comprising, a switch point operating link having a pin engaging slot formed therein and capable of moving in a straight line only, 15 a lock mechanism operating link having a pin engaging slot formed therein, a crank shaft, and pins on said shaft for engaging the slots formed in the separate links, said slots being so formed that one link is moved 20 while the other is stationary.

5. A switch operating mechanism comprising, a switch point operating link, capable of moving in a straight line only and having a pin engaging slot formed therein, 25 a lock bar operating link, capable of moving in a straight line only and having a pin engaging slot formed therein, a crank shaft for actuating said links and pins mounted on the crank shaft for engaging the slots 30 formed in the links, said slots being so formed that the lock bar operating link is shifted while the switch point operating link is stationary, and then the switch point operating link is shifted while the lock bar 35 operating link is stationary.

6. In a switch operating mechanism, a switch-point actuating link, a lock-bar actuating link parallel to the switch-point actuating link, and a shaft adapted successively to impart longitudinal movements to the lock-bar actuating link, the switch- 40

point actuating link, and then the lock-bar actuating link, when it is turned from one position to the other.

7. In a switch operating mechanism, a 45 switch-point actuating link, a lock-bar actuating link parallel to the switch-point actuating link, rods at each of the ends of the switch-point actuating link and of the lock-bar actuating link, adapted to connect 50 the switch-operating mechanism with both of the switches of a cross-over, and a shaft for successively imparting longitudinal movements to the lock-bar actuating link, the switch-point actuating link, and then 55 the lock-bar actuating link, whereby when it is turned from one position to the other, both the switches are first unlocked, then both switches are actuated, and then both switches are again locked. 60
